UNITED STATES PATENT OFFICE.

JOSEPH SIEWERT AND MICHAEL WISNIEWSKI, OF CHICAGO, ILLINOIS.

TRANSOM-LIFTER.

SPECIFICATION forming part of Letters Patent No. 632,326, dated September 5, 1899.

Application filed March 31, 1899. Serial No. 711,248. (No model.)

To all whom it may concern:

Be it known that we, JOSEPH SIEWERT and MICHAEL WISNIEWSKI, citizens of the United States, residing at Chicago, Illinois, have invented certain new and useful Improvements in Transom-Lifters, of which the following is a specification.

The object of our invention is to provide a simple, economical, and efficient transom-lifter; and the invention consists in the features, combinations, and details of construction hereinafter described and claimed.

In the accompanying drawings, Figure 1 is a front elevation of a transom supplied with our improvements; Fig. 2, a side elevation of the same, shown partly in section, with the transom in its closed position; Fig. 3, a similar view showing the transom in a partially-open condition; and Fig. 4, a sectional elevation of a portion of the mechanism, taken on the line 4 of Fig. 1, looking in the direction of the arrow.

In the art to which this invention relates it is well known that ordinarily transoms are pivotally connected with the supporting-frame, so that they turn on pivots, and are opened by means of lifting mechanism of various constructions. There are objections to this class of transoms and their lifting apparatus when used with large and heavy transoms, such as are used over the doors of mercantile establishments and stores, in that the entire weight of the door is taken upon two small pivots and the transom swings inside as well as outside.

The principal object of our invention, therefore, is to remove any of these objections which are found in connection with transoms of this large type and provide sustaining and lifting mechanism which will hold the transom in the desired positions and which is economical to construct and simple and efficient in operation, all of which will more fully hereinafter appear.

In constructing our improvements, as shown in the drawings, we use an ordinary supporting-frame A, having a door-opening a and provided with a frame B above the same. To sustain the frame in its different positions, we provide an inverted-U-shaped rock-shaft C, which has two depending arms c, to which the frame is pivoted by means of the brack-

ets C', that are secured to the door by means of ordinary wood-screws. From this construction it will be seen that the transom is 55 swung out from its closed position, as shown in Figs. 3 and 4, and that the heel c' of the transom bears against the supporting-frame, as shown in Figs. 3 and 4. In this way the frame can be made to open inwardly into the 60 store-room entirely, and thus avoid the catching of the dirt and rain from the outside, and at the same time the weight of the heavy transom is divided between the rock-shaft and the frame, thus holding the frame at several 65 points and more securely than when it is merely held upon two pivots, while at the same time the transom is much more readily inserted into position or removed therefrom whenever occasion requires or necessity demands.

To lift the transom and hold it in its various positions, we provide a lifting-rod D, which is connected with a lever-arm E, that is pivotally connected to one of the depending arms of the rocker-shaft by means of the link G and the C-shaped clip g. As the lifting-rod is raised (see Fig. 3) the connecting-link tends to assume a horizontal position, which action forces the depending arms of 80 the rocker-shaft outwardly, thereby carrying the transom on its pivot outwardly, and as the superior weight of the transom is above the pivotal points the transom also tends to assume a horizontal position; but the heel of 85 the transom bearing against the door-frame holds it at an angle until it is entirely raised, thus opening the same gradually to one side of the frame. A bracket H is provided and secured to the door-frame, through which the 90 lifting-rod is passed. This bracket is provided with a thumb-screw h, adapted to press against the lifting-rod, and thereby hold it in any desired position and also hold the transom in such position.

It is desirable to provide stop mechanism which will limit the upward movement of the transom and at the same time take part of the weight of the transom, and in order to accomplish this result we prefer to provide a 100 U-shaped stop-rod I and drive it into the door-frame, as shown in Figs. 1 and 4. The transom is provided with a stop-lug K, that is adapted to bear against the upper portion

of the stop-rod when the transom reaches its most open position, which is substantially a horizontal plane. The C-shaped clip on the lifting-rod is also arranged to contact a bracket II on the door-frame, and the transom has a second stop-lug K', which has its free end projecting through the opening formed by the C-shaped clip, as shown in Fig. 3, so that when the transom is in its most open position these stop-lugs rest against their respective stops and take a portion of the weight from the pivots.

The lever-arm E, as above stated, is pivotally connected to one of the depending arms 15 of the rock-shaft and has a projecting portion e, adapted to rest against such depending arm, as shown in Fig. 2, when the parts are in their closed position.

A projecting lug d' is formed on the lifting-rod and adapted to bear against the free 20 end of the stop-lug K' when the parts are in their open position and during the initial downward movement of the lifting-rod. This projection lug forces the lower end of the 25 transom downwardly, and thus assists in the closing operation.

We claim—

1. In an apparatus of the class described, the combination of a loosely-mounted transom, a 30 rocker-shaft provided with a depending-arm mechanism pivotally secured to the transom to sustain all of the weight of the transom, and mechanism for moving the depending arms of the rocker-shaft outwardly and inwardly 35 to open and close the transom, substantially as described.

2. In an apparatus of the class described, the combination of a U-shaped rocker-shaft adapted to be secured to a frame above the 40 transom so that its arms depend therefrom, a transom pivotally connected to the depending arms of the rocker-shaft, a lifting-rod, a link mechanism connecting the lifting-rod with the depending arms of the rocker-shaft 45 to move the same and open and close the transom, substantially as described.

3. In an apparatus of the class described, the combination of a U-shaped rocker-shaft arranged to be pivotally secured to a frame 50 or similar portion above the transom so that its arms depend therefrom, a transom pivotally connected with the depending arms of the rocker-shaft, a vertically-movable lifting-rod, a lever-arm pivotally connected to one of 55 the depending arms of the rocker-shaft, a link connecting the lever-arm with the lifting-rod and stop mechanism for limiting the upward

movement of the lifting-rod and adapted to bear against the inner end of the transom, substantially as described.

4. In an apparatus of the class described, the combination of a U-shaped rocker-shaft arranged to be secured to a frame or similar portion above a transom so that its arms depend therefrom, a transom pivotally connected 65 with the depending arms on the rocker-shaft, a lever-arm pivotally connected with one of the depending arms, a C-shaped clip on the lifting-rod, a link pivotally connecting the lever-arm of the rocker-shaft with the C- 70 shaped clip, a stop-lug on the inner end of the transom passed through the opening formed by the C-shaped clip, and stop mechanism on the frame portion to assist in limiting the upward movement of the vertical rod and transom, substantially as described.

5. In an apparatus of the class described, the combination of a U-shaped rocker-shaft arranged to be secured to a frame or similar portion above a transom so that its arms depend therefrom, a transom pivotally connected 80 with the depending arms on the rocker-shaft, a lever-arm pivotally connected with one of the depending arms, a C-shaped clip on the lifting-rod, a link pivotally connecting 85 the lever-arm of the rocker-shaft with the C-shaped clip, a stop-lug on the inner end of the transom passed through the opening formed by the C-shaped clip, stop mechanism on the frame portion to assist in limiting the upward 90 movement of the vertical rod and transom, and a free projecting end on the lever-arm adapted to contact one of the depending arms of the rocker-shaft when the parts are in their closed position, substantially as described.

6. In an apparatus of the class described, the combination of a U-shaped rocker-shaft adapted to be secured to a frame or similar portion above a transom, a transom pivotally connected to the depending arms of the 100 rocker-shaft, a vertically-movable lifting-rod, a C-shaped clip on the vertically-movable lifting-rod, a pivotal lever-arm on the depending arm of the rocker-shaft, a stop-lug on the inner end of the transom with its free end passed 105 through the opening formed by the C-shaped clip, and a projection on the lifting-rod adapted to contact this stop-lug and assist in the closing operation, substantially as described.
